UNITED STATES PATENT OFFICE.

JOHN M. MCCLATCHIE, OF NEW YORK, N. Y., ASSIGNOR TO THE BORDEN COMPANY, OF NEW YORK, N. Y., A CORPORATION OF NEW JERSEY.

PUMP.

Application filed November 29, 1926. Serial No. 151,204.

The invention relates to an improvement in pumps, and more particularly to an improvement in pumps of the gear type.

Pumps of this type usually comprise a casing in which is located a pair of intermeshing gears the teeth of which serve as the pumping member. These pumps have been found highly efficient for the purpose of withdrawing liquid from a storage tank or the like and delivering it to a point at which it is to be acted on. The pumps of this type as heretofore constructed, however, have proven objectionable for pumping milk. Owing to the fact that milk sours quickly, the fibrous packings with which these pumps have been provided have had to be replaced daily, an operation involving expense and delay. The object of the present invention is to produce a gear pump of such construction that the necessity for fiber packings is eliminated, so that the pump may be cleaned without disassembling; or if disassembling is required, it may be done with a minimum of difficulty and time consumption because of the simplicity of construction of the pump. To this end the invention consists in the improved pump of the gear type hereinafter described and particularly pointed out in the appended claims.

In the accompanying drawings illustrating the preferred form of the invention, Fig. 1 is a longitudinal section through the improved pump; and Fig. 2 is a transverse section, on a reduced scale, taken along the line 2-2 of Fig. 1.

The improved pump as illustrated in the drawings comprises two equal size intermeshing gears 5 and 6 enclosed within the casing 7 provided on its front side with the cover 8. The upper gear 5 is mounted on a shaft 9 journaled at one end in the pocket 10 formed in the casing and at the other end in the pocket 11 formed in the cover 8. The lower gear 6 is secured by a key 12 to a cup-like hub part 14 of a shaft 16 journaled at its forward end in the casing and cover and at its rear end in the journal block 17. The casing 7 and journal block 17 are connected together and supported from a base or frame 18. The shaft 16 is driven by means of the gear 19 and the direction of rotation is such that the milk or other fluid is drawn into the inlet 20 of the casing to discharge through the outlet 21, as indicated by the arrows in Fig. 2, the liquid being carried between the teeth of the gears and the adjacent parts 22 of the cas-

ing. The shaft 16 is jointed at the point 23 to facilitate the disassembling of the pump without disturbing the gear 19.

Since the gear 5 and the shaft 9 are entirely enclosed by the casing 7 and cover 8 it is unnecessary to provide them with washers to prevent leakage. Inasmuch, however, as the shaft 16 of the gear 6 projects through the casing it is necessary to provide packing means at this point to prevent leakage. This packing means must be so arranged that the pump may be quickly disassembled and assembled again if necessary, or if that is not considered desirable, must be of such a nature that milk will not adhere to it and sour. In the arrangement shown I interpose between the disk part or bottom 25 of the hub 14 and the adjacent part 26 of the casing a metal washer 27. The disk part 25 of the hub 14 is pressed tightly against the washer 27 and the latter against the adjacent part 26 of the casing by means of the expansion spring 28 located within the circumferential recess 29 of the hub 14, one end of the spring bearing against the disk 25 and the other end of the spring bearing against a washer 30 which snugly surrounds the outer end of the shaft 17 and is forced by the spring 28 against the adjacent part 31 of the cover 8. The washer 30 fits within a recess 32 in the outer end of the hub 14.

The washers 27 and 30 are preferably made of hardened metal so that they may be ground to assure perfect alinement and therefore a tight joint at the point where the washer 27 is interposed between the disk 25 and the adjacent part 26 of the casing. In order to facilitate the disassembling of the pump parts the spline 12 is fitted tightly into either the gear 6 or hub 14 and has a sliding connection with the other member.

Having thus described the invention what I claim as new is:

1. A pump of the class described comprising, a casing having an inlet and an outlet, a pair of intermeshing gears located in the casing, a shaft for the first gear journaled within the casing, a shaft for the second gear journaled in the casing and extending through one side thereof, means for driving the second shaft, a hub formed on the second shaft and on which the second gear is mounted, a metal washer interposed between one end of the hub and the adjacent part of the casing, a second metal washer interposed between

the other end of the hub and the adjacent part of the casing, the hub being provided with a recess surrounding the shaft, and a spring located in the recess and pressing at 5 one end against the hub to force the first washer against the adjacent part of the casing and pressing at the other end against the second washer.

2. A pump of the class described comprising, a casing having an inlet and an outlet, 10 a pair of intermeshing gears mounted in the casing, a driving shaft for one of the gears projecting through the casing, a cup-shaped hub on the driving shaft for supporting the 15 second gear, a metal washer interposed between the disk part of the hub and the adjacent part of the casing, and a spring received within the cup-shaped hub and pressing at one end against the disk part of the hub and 20 at the other end against the opposite wall of the casing.

3. A pump of the class described comprising, a casing having an inlet and an outlet, 25 a pair of intermeshing gears mounted in the casing, a shaft for one of the gears projecting through the casing, an enlargement on the shaft for supporting the second gear, a washer interposed between the enlargement

and the adjacent part of the casing, and means for resiliently forcing the enlargement 30 against the washer and the latter against the casing.

4. A pump of the class described comprising, a casing having an inlet and an outlet, 35 a pair of intermeshing gears located in the casing, said gears being of substantially the same thickness as the depth of the chamber, a shaft for the first gear journaled in the side walls of the casing, a shaft for the second gear journaled in the side walls of the 40 casing and extending at one end through one of the walls, means for driving the second shaft, a cup-shaped hub formed on the second shaft and on which the second gear is mounted, a metal washer of substantially the 45 same diameter as the hub interposed between the outer side of the bottom end of the hub and the adjacent wall of the casing, a second washer slidingly received within the free 50 end of the hub, and a spring located within the hub and acting on the second washer to force it against the adjacent wall of the casing and on the bottom of the hub to force the first washer against the adjacent wall of the casing.
